MECHANICAL PENCIL

Benjamin Zelenitz, Brooklyn, N.Y.

Application May 29, 1946, Serial No. 673,107

16 Claims. (Cl. 120—9)

1

This invention relates to devices such as mechanical pencils.

One object of the invention is to provide a device of the character described having improved means for the continuous automatic feed of an element, only as the same is consumed.

The element referred to includes a plurality of rod-like parts which converge to an operating point at which they laterally, angularly abut each other to resist and prevent feeding thereof except as the operating portion is consumed, there being a means for evenly advancing both rod-like parts by exerting a constant pressure thereon which may be of yielding nature or merely so weak as to be ineffective to overcome the resistance at the operating portion of the parts. Accordingly the point of lateral abutment travels along the rod-like parts as the same are consumed, the feeding occurring only as these parts are consumed and in proportion to the speed of consumption. The rod-like parts may converge to a relatively fine point by making the same generally half round in cross section, and the feeding means maintains these parts in such relation. Since the advancing means may be relatively weak, as stated, a one-way clutch may serve to resist reverse movement of the rod-like parts. The latter may consist of pencil leads, welding rods and similar devices, but the advantages of the invention are best exemplified in a mechanical pencil, which is believed to be a field of invention different from welding devices and the like.

It is, therefore, an object of the invention to furnish a device such as a mechanical pencil having improved self-feeding means, with associated means to prevent reverse movement as where the elements or leads are subjected to pressure in writing or in other operations.

Another object of the invention is to furnish a mechanical pencil in which relatively long elements or leads are sprung to arcuate paths to thus increase the angle of convergence within the relatively narrow limits of a pencil.

Another object of the invention is the provision of a mechanical pencil having improved means comprising relatively few and simple parts and which is inexpensive to manufacture and assemble, durable, reliable, and highly efficient in use.

Other objects and advantages of the invention will become apparent as the specification proceeds.

With the aforesaid objects in view, the invention comprises the novel features, combinations and arrangements of parts hereinafter described in their preferred embodiments, pointed out in

2

the subjoined claims, and illustrated in the annexed drawing, wherein like parts are designated by the same reference characters throughout the several views.

In the drawing:

Fig. 1 is a central longitudinal sectional view with parts removed showing a mechanical pencil embodying the invention.

Fig. 2 is a view like that of Fig. 1 but partly in elevation and partly in section along a central longitudinal plane, with parts removed.

Fig. 3 is a view at right angles to the foregoing with parts in elevation, parts in section, and parts removed, showing the pencil in course of being assembled with its cover, the clutch being inoperative position.

Fig. 4 is an enlarged sectional view of the leads separated from each other at a point along their convergent paths.

Fig. 5 is a similar view but showing the leads in lateral engagement with each other at a point of the common writing end portion formed by the leads.

Fig. 6 is an enlarged fragmentary sectional view, with parts removed, showing the clutch in operative position.

Fig. 7 is a sectional view on line 7—7 of Fig. 6.

Fig. 8 shows a modification with arcuate paths for the leads.

Fig. 9 is a transverse section of the device of Fig. 8 showing the modified lead retaining means for the arcuate paths.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a device such as a mechanical pencil embodying the invention. The same may include a core member having tapered point portion 11 from which there extends axially a core element 12 and an annular internally and externally threaded sleeve 13 extending about the adjacent portion of the core element. The parts 11, 12 and 13 may be of one-piece construction. A cover 14 is adapted to axially receive the core element 11 and is removably connected to the sleeve 13 at its

external thread to thus abut the adjacent shoulder 15 of the point portion 11.

Provided by the core member 11, 12 is a guide means affording convergent paths for the leads 16 such that the leads come into lateral abutment with each other at a point 17 beyond the end of the point portion 11, to form a common writing portion at 17. Preferably the leads are of generally half-round form with their flat faces 18 maintained by the guide means in confronting relation to each other as shown in Fig. 4, these faces coming into contact with each other adjacent to the writing point 17 as shown in Fig. 5.

Illustratively, the guide means include the generally cylindrical core element 12 having openings 19 formed therein along a diametrical plane. These openings in the core element 12 constitute longitudinal slots open at the periphery thereof. The slots disappear at the curved free end portion of the core element. Adjacent to the opposite end of the latter, they lead at 21^a into the bores or holes 22 which are aligned with the slots and extend through the point portion 11. The slots 19 and the openings 22 afford straight, continuous, convergent paths for the leads 16. Such paths are provided by the base portions of the slots 19, these base portions providing flat or plane seats 23 conforming to the flat faces 18 of the leads 16, and the bores 22 may be correspondingly shaped if desired for example to the half-round configuration.

A feeding means may include a common element 24 for the leads movable along a diametrical slot opening 25 of the core element 12. This slot 25 intercommunicates the lead guide slots 19 but is substantially narrower than the latter; thus the seats 23 are split, but they have sufficient bearing area for the leads 16. The element 24 may be connected to or form a part of a single tension coil spring 26 taking around the core element 12 which forms a guide therefor, this spring being removably threaded into the inner thread of the sleeve 13. Thus there is a common structure applying the same pressure on both leads 16, with the element 24 bearing on the inner ends thereof, the parts cooperating to tend to keep the leads seated on the seats 23.

The spring 26 represents any feeding means which is of yielding character or so weak that it cannot overcome the obstruction afforded by the lateral abutment of the convergent leads at the common writing point 17 but being capable of continuously automatically advancing the leads as the writing point wears down, and when the writing pressure on the leads is momentarily relieved. Of course, the spring tension becomes weaker as the feed of the leads progresses. For these reasons, and to strongly resist the writing pressure on the leads, a one-way clutch is provided adapted to readily travel with the spring but resisting reverse movement of the leads. For a uniform balanced effect, the feeding means includes a plurality of clutch elements or detent means 27. Each may be formed like a U-shaped or spring clip having a loop 28 clipped around a coil of the spring 26 from which loop extend the legs 29, 30. The legs 30 are adapted to ride along the cover 14, while the legs 29 are received in longitudinal slots 31 of the core element 12, these legs 29 being preferably inwardly bowed to afford springs adapted to frictionally grip the core element at the ends of these legs. The gripping surface is at the bases of the diametrically arranged slots 31, and the latter may extend around at 32 the curved end 21 of the core element,

whereby the clutches 27 may be moved to the inoperative positions shown in Fig. 3. When the cover 14 is removed, the clutches 27 expand and hence would obstruct replacement of the cover. To avoid such obstruction, the operator moves the clutches to the position of Fig. 3, the curved slots or openings 32 affording clearance for the legs 29 to permit the clutches to be swung toward each other about the spring mounting coil as a pivot. As the lead feeds forward to writing position, the spring 26 advances the clutches 27 which thereupon swing outwardly away from each other to the position shown in Fig. 6, with the legs 29, 30 becoming deflected toward each other to a compressed operative position conjointly maintained by the core element and the cover. The slots 31, 32 afford continuous guiding engagement for the clutches. And in the operative position thereof, the clutches will not interfere with removal of the cover nor will the clutches be shifted by rotary or longitudinal movement of the cover in course of its removal.

In use, the pencil is loaded by removing the cover 14 and unscrewing the spring 26 from the sleeve 13, thus removing with it the feeding element 24 and the clutches 27. Then the leads 16 are placed in the guide slots 19 and moved into the guide holes 22. Now the spring is applied and engaged with the sleeve 13, while stretched so that the element 24 clears the core 12. The element is now inserted in the slot 25 and the spring permitted to contract so that the element 24 feeds the leads 16 forwardly while the clutches 27 assume their positions shown. These clutches may be adapted to ride around the spring and the same applies to the element 24, but preferably these parts have fixed diametrical positions on the spring. Now the cover 14 is applied and as the feeding progresses, the clutches swing to the operative positions shown in Fig. 6. The leads 16 having their flat faces 18 continuously confronting each other and abut at the writing end 17 to obstruct outward movement under the spring pressure except as the end 17 wears down, causing progressive shifting of the abutting portions along the leads. Writing pressure is resisted by the clutches 27. A common, compact writing point is afforded which is always uniform since the leads are evenly fed, and writing pressure will not cause the abutment relation to break the leads because such pressure tends rather to diminish the abutment pressure.

In Figs. 8 and 9 is shown a modified pencil 35, differing principally in that the leads 36 are caused to assume arcuate convergent paths as shown to thus increase the angle of convergence adjacent to the writing end 37, and increase the abutment relationship thereat. This is accomplished by springing the leads, utilizing a guide and feeding means like that of the pencil 10, except that the core element 12 is modified in cross section as shown by the core 38 of Fig. 9. This core is distinguished in that the lead guide slots 19 here denoted as 39 are contracted at 40 to a width equal to that of the slot 25 to afford snug fitting guides for the bowed or sprung leads to thus avoid further springing and breakage thereof under longitudinal pressure. The feed element is thus guided by the openings 40 as well as by the slot 25. The core 38 may also be used with advantage in the pencil 10.

I claim:

1. A mechanical pencil having means for guiding a plurality of leads along lines so convergent that the leads laterally abut each other at their

outer ends to form a writing point, and spring means for feeding said leads as the abutting ends become worn out in writing.

2. A mechanical pencil having means for continuously automatically and simultaneously guiding and feeding a plurality of leads, including means to cause the outer end portions of the leads to converge substantially to a point and thus to obstruct and arrest their feed except as the end portions become worn out in writing to permit the leads to feed until they again obstruct each other and arrest the feed.

3. A mechanical pencil having means for guiding a plurality of leads along convergent paths so that the writing end portions of the leads meet substantially at a common writing point, and means for yieldingly continuously urging advance of the leads as the end portions become worn but being otherwise insufficient in strength to advance the leads.

4. A mechanical pencil having guide means having convergent paths for a plurality of leads such that the leads meet at a common writing point and abut each other to thus arrest the feed of the leads, means for continuously yieldingly urging the leads to advance under equal pressure as the point becomes worn but being otherwise incapable of advancing the leads, and means for resisting reverse movement of the leads under writing pressure.

5. A mechanical pencil having means for guiding a plurality of leads along convergent paths such that the leads meet to form a common writing point, said leads being approximately half-round in cross section, the guiding means having means for maintaining the leads in such relation to each other that their flat surfaces meet at said writing point.

6. A mechanical pencil including means for holding a plurality of generally half round leads so that their flat faces confront each other, including means for guiding said leads along convergent paths so that the leads laterally abut each other at their flat faces to form a common writing point, and feeding means for advancing the leads as the common writing point wears down, the feeding means being so relatively weak and the said abutment being sufficient to resist the feeding means except as the common writing point wears down.

7. A mechanical pencil including guide means for a plurality of generally half round leads along convergent paths and having seats to cause the flat faces of the leads to confront each other, with the leads meeting at a common writing point at which they abut each other at their flat faces, and means for feeding the leads to equally advance the same.

8. A mechanical pencil including guide means providing convergent paths for a plurality of leads so that the latter meet and laterally abut each other at a common writing point, the guide means having a plane seat for the flat faces of the leads to maintain the faces in confronting relation to each other, and feeding means constantly urging the leads to advance, the angle of convergence adjacent to the writing point being sufficient to prevent the leads from advancing except as the writing point becomes worn

down so that the area of abutment is transferred to next adjacent portions of the leads upon advance thereof by the feeding means.

9. A mechanical pencil according to claim 5, wherein the feeding means include a common spring for advancing the leads.

10. A mechanical pencil according to claim 5 wherein the guide means includes a core having longitudinal convergent guide openings for the leads and longitudinal passages communicating with said openings, the feeding means having a common spring for the leads coaxial with the core and having portions in said passages and openings to feed the leads at different points along their convergent path.

11. A mechanical pencil according to claim 5 wherein the feeding means includes a yieldable feeding element and detent means inoperative upon advancing movement of the leads but resisting reverse movement thereof under writing pressure on the leads.

12. A mechanical pencil according to claim 5 wherein the convergent paths include arcuate sections to vary the convergence and increase the same toward the writing point.

13. A mechanical pencil having guide means defining arcuately convergent paths for a plurality of leads, and means for feeding the leads simultaneously along said paths.

14. A mechanical pencil comprising means for yieldably feeding a lead including an elongated core member, a tension coil spring positioned about said core member for supplying the feeding force, an elongated cover fitted to include said core and spring, and a one-way detent means pivoted on a coil of said spring engaging said core and cover for resisting reverse movement of the lead.

15. A mechanical pencil comprising means for yieldably feeding a lead including an elongated core member, a tension coil spring positioned about said core member for supplying the feeding force, an elongated cover fitted to include said core and spring, and a one-way detent means pivoted on a coil of said spring engaging said core and cover for resisting reverse movement of the lead, said detent means and core being so constructed and arranged as to permit the detent means to pivot out of the way of the cover to facilitate mounting the latter and to return to operative position between the core and cover upon advance of the detent means in course of feeding the lead.

16. The mechanical pencil defined in claim 14 including divergent lead guiding passages in the core whereby the leads abut each other laterally to form a common writing point and thus resist feeding of the leads by said feeding means.
